UNITED STATES PATENT OFFICE.

JACOB BUTSCH, OF LYNNVILLE, INDIANA.

DEVICE FOR REMOVING KEYS FROM SHAFTING AND PULLEYS.

986,133.

Specification of Letters Patent.

Patented Mar. 7, 1911.

Application filed May 7, 1910. Serial No. 560,035.

To all whom it may concern:

Be it known that I, JACOB BUTSCH, a citizen of the United States, residing at Lynnville, in the county of Warrick and State of Indiana, have invented a certain new and useful Improvement in Devices for Removing Keys from Shafting and Pulleys; and I do hereby declare the following to be a full, clear, and exact description of the same, reference being had to the accompanying drawings, forming a part of this specification, and to the figures and letters of reference marked thereon.

This invention relates to devices for facilitating the removal of keys employed for connecting shafting and pulleys, fly-wheels, etc., and which are ordinarily removed by a relative longitudinal movement.

The objects of the invention are to provide a simple and convenient device, the use and operation of which will be readily comprehended and which is capable of wide range of usefulness to meet various conditions and arrangements of pulleys, shafting, etc.

The invention consists in certain novel details of construction and combinations and arrangements of parts, all as will be now described and pointed out more particularly in the appended claims.

Referring to the accompanying drawings—Figure 1 is an elevation of the device in position to assist in the removal of a key from a pulley and shaft, the latter being indicated diagrammatically. Fig. 2 is a top plan view of the device with the shaft and key in dotted lines, and Fig. 3 is a perspective view of the key gripping end of the device showing the shape of the gripping jaws.

Like letters of reference in the several figures indicate the same parts.

The body of the device is in the form of a vise or key gripping member, preferably embodying crossed-levers or arms A pivotally connected together at B and having their shorter ends formed into key-gripping jaws C. The key-gripping jaws preferably have biting edges, elongated transversely, as shown in Fig. 3, so as to grip the key in a manner not only calculated to prevent slipping, but also to prevent swinging or pivotal action of the device with the gripping points as a center. For clamping the jaws on the key the arms A are conveniently connected by a transverse bolt D, on one end of which is an adjusting nut d, whereby the

arms may be drawn together and the gripping jaws set up with any desired degree of pressure, so as to insure a proper holding action.

60

Obviously, the relative length of the ends of the arms on opposite sides of the pivotal point should be made such as to insure a sufficient hold on the key, and to this end the transverse bolt or vise screw is preferably located 65 some distance away from the pivot to give an increased leverage. The outer or longer arms of the members A are extended some distance beyond the vise screw and at their extremities are provided with bearings for 70 the cross-head E, said bearings being conveniently open bearings f formed on the inner edges of transverse extensions F of the members A. There may be, as shown, a plurality of such bearings for a purpose which 75 will presently appear.

The crosshead E is provided centrally with a transverse threaded aperture in which works a long screw G, the inner end of which is somewhat pointed as at g and 80 its outer headed end squared or formed for the reception of a wrench or power appliance as at g', whereby the screw may be turned.

In making use of the device, the body or 85 vise jaws are securely clamped on the key, as indicated in the drawings with the transverse projections F in line with the shaft. The crosshead is then placed in position with the end of the screw bearing on the end of 90 the shaft after which sufficient power is applied to the screw to tighten the device and exert a considerable pressure on the key itself, tending to withdraw it longitudinally. If the key is easily movable it 95 may be removed by continuing to turn the screw, but in most instances it is found desirable at this point to strike the pulley or part held to the shaft by the key, with a hammer and in a direction reverse to the 100 direction in which the key is being removed. The shock of the blow will usually be sufficient to slightly loosen the pulley on the key and shaft, whereupon by further turning the screw the key may be easily withdrawn.

By providing a plurality of bearings for the crosshead, the pressure of the withdrawing screw may be brought to bear at the axes of shafts of different size and this 110 is desirable especially as shafting usually is provided with a central recess or center.

in which the screw may conveniently find its bearing.

By the provision of elongated gripping edges on the jaws the tendency of the device to rotate about the gripping point when the pressure of the withdrawing screw is brought to bear, is to a great extent overcome but should any tendency to rotate about the gripping point manifest itself, the body or vise member may be held or braced from any suitable external point, although this will not ordinarily be found to be necessary, as the length of the members A is such that they can be easily held by hand to prevent them from getting out of alinement, even should the gripping edges of the device be insufficient for this purpose. A further advantage in the particular construction illustrated results from the employment of a relatively long withdrawing screw and the location of the crosshead and its bearings a considerable distance from the gripping jaws, for with this arrangement it becomes possible to reach and remove keys located a considerable distance from the end of a shaft and this feature is of particular advantage where the device finds its field of usefulness in connection with agricultural machinery, threshers, etc., in which there is little or no uniformity followed in the location of pulleys on the shafts.

The device is an exceedingly simple and handy structure well adapted for universal shop and field purposes.

Having thus described my invention, what I claim as new and desire to secure by Letters Patent of the United States is—

1. In a device such as described, the combination with members pivotally connected

together and having at one side of the pivotal point coöperating elongated gripping jaws and at the opposite side of said pivotal point transverse extensions having bearings therein for a crosshead, and a transverse screw for holding the jaws in gripping position, of a crosshead removably mounted in said bearings and a withdrawing screw threaded in said crosshead and adapted to coöperate with the end of the shaft carrying the key to be withdrawn.

2. In a device such as described, the combination with a vise member embodying pivotally connected jaws having transversely elongated gripping edges, a jaw holding screw for securing the jaws in gripping position and extensions having open bearings therein, of a crosshead removably mounted in said open bearings and a relatively long withdrawing screw threaded through said crosshead and having its inner end pointed and its outer end provided with a head for the application of a power member.

3. In a device such as described, the combination with the members A pivotally connected together and having on their shorter ends key gripping jaws and on their longer ends transverse projections F provided with open bearings in their inner edges, of a transverse screw for holding the jaws in closed position, a crosshead removably seating in said open bearings, and an elongated withdrawing screw threaded through said crosshead, substantially as described.

JACOB BUTSCH.
